(57) **CLAIM**

The ornamental design for a door sill guard set, as shown and described.

DESCRIPTION

FIG. 1 is a perspective view of the door sill guard set showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof.

FIG. 9 is an enlarged view of a portion indicated with numeric 9 in FIG. 1; and,

FIG. 10 is a cutaway view of a portion indicated with numeric 10 in FIG. 3.

The dot-dash lines viewed in FIGS. 1, 9 are for the purpose of depicting boundaries of the enlarged views and form no part of the claimed design.
